UNITED STATES PATENT OFFICE.

BURT A. PETERSON, OF ROCKFORD, ILLINOIS, ASSIGNOR, BY MESNE ASSIGNMENTS, TO BARBER-COLMAN COMPANY, OF ROCKFORD, ILLINOIS, A CORPORATION OF ILLINOIS (1922).

KNOT-TYING IMPLEMENT.

Application filed April 1, 1920. Serial No. 370,395.

To all whom it may concern:

Be it known that I, BURT A. PETERSON, a citizen of the United States, residing at Rockford, in the county of Winnebago and State of Illinois, have invented certain new and useful Improvements in Knot-Tying Implements, of which the following is a specification.

The invention relates to knot-tying devices such as are used in textile mills, and more particularly to that type which is adapted to be supported upon the hand of the mill operative and operated by a manipulation of the thumb to unite the ends of thread or yarn.

The general object of the invention is to provide a knotter of improved construction in which the parts are advantageously arranged, providing a device which is efficient in operation, may be cheaply manufactured, and is capable of withstanding long and hard usage.

A further object of the invention is to provide a knotter of improved construction in which the actuating mechanism is compactly arranged and wholly enclosed within a casing so as to be protected against dust and lint.

In the drawings wherein I have illustrated a preferred embodiment of the invention, Figure 1 is a side elevation of the improved knotter. Fig. 2 is a central vertical sectional view through the knotter taken substantially on the line 2—2 of Fig. 1. Fig. 3 is a similar view taken in the plane of line 3—3 of Fig. 2. Fig. 4 is a vertical sectional view taken in the plane of line 4—4 of Fig. 2.

The knotter comprises generally an annular casing 1 having rotatably mounted diametrically thereof a stem or spindle 2 carrying at one end a tying bill 3 and having rigid therewith a pinion 4. On opposite sides of the casing are mounted a thread guide member 5 and a clamping device 6.

In the present embodiment of the invention the guide members 5 and 6 are stationary with reference to the casing and the tying bill 3 is adapted to be swung to effect the rotation thereof and, in such rotation, the tying of threads held in operative relation therewith and the guide member 5 and clamping device 6. For thus swingably supporting the tying bill 3, and the spindle 2 by which the bill is carried, the spindle is

mounted in an oscillatory frame or bracket 7 mounted coaxially within the casing and operable in one direction by means of a thumb lever 8. A spring 9 serves to restore the parts to their normal position. To effect the rotation of the tying bill in such swinging movements, the pinion 4 meshes with an arcuate rack or gear segment 10 rigid with respect to the casing 1.

The casing 1 is cylindrical in shape and preferably is made from two interfitting sections 1^a and 1^b, which sections may be secured together in any suitable way. The section 1^a has rigidly secured upon its side wall a depending hand portion 11 slotted to receive a strap (not shown) by means of which the device may be mounted upon the hand of the operator. In the upper portion of the section 1^b is a slot 12 through which the tying bill extends, said slot serving to limit the swinging movements of the tying bill.

The stem or spindle 2 and the pinion 4 are preferably formed integral with each other, and the tying bill 3 is suitably mounted at the upper end of the spindle. The bracket 7 is mounted upon a central tubular stem 13 rotatably mounted in the casing. Said bracket comprises a plate or disk portion 7^a having an arcuate flange portion 7^b and an oppositely disposed bearing lug 7^c. Said lug provides a bearing for one end of the spindle and to support the opposite end a bearing member 15 is secured within the arcuate flange portion 7^b of the bracket 7, which is located immediately within the peripheral wall of section 1^b of the casing. Said flange portion is made of a length adapted in all positions of the tying bill relative to the casing to close the slot 12. The member 15 has a socket 16 therein formed eccentrically with reference to the spindle and forming a cam barrel adapted in the rotation of the spindle to effect the operation of the tying bill in the manner well known in the art. To receive the spindle the tubular stem is perforated transversely thereof, and to hold the spindle in operative position in the casing it is provided with an annular groove 17 centrally thereof into which projects the reduced inner end 18^a of a stud 18 carried by the casing section 1^b. Said stud is rigidly mounted upon the side wall of the casing section 1^b and fits neatly within the end of 110

105
110

the tubular stem 13 to form a pivot therefor. When the spindle 2 is thus maintained in operative position, the pinion 4 is held in mesh with the arcuate rack member 10, which latter is rigidly secured to the section 1^a of the casing immediately adjacent the bearing member 7^c of the bracket 7.

The thread guide member 5 is formed on the upper end of a plate 19 approximately 10 circular in form and rigidly secured to the side wall of the casing section 1^b, the guide 5 being formed on the periphery of said plate and projecting upwardly and slightly outwardly from the upper edge thereof as 15 shown in Fig. 2. The member is in the form of a hook and for the purpose of guiding the thread into the hook has a rounded guiding edge 5^a (Figs. 1 and 2).

The thread clamping device 6, which is 20 carried by the casing 1 upon the side wall opposite the guide member 5, comprises a pair of stationary plates 20 and 21 providing stationary jaws 22 and 23 adapted to cooperate with a movable jaw 24 formed on 25 an intermediate member 25. The members 20 and 21 are respectively secured to the peripheral and side walls of the casing section 1^a, and the intermediate member 25 depends through a suitable opening in the 30 peripheral wall of said section into the casing (Fig. 4). At its lower end said member 25 may be bifurcated to form a yoke member 26 adapted to straddle a washer 13^a on the stem 13, and if desired a bearing piece 35 or boss 25^a for the forward edge of the member may be provided on the adjacent side wall of the casing. Immediately above said yoke 26 the member 25 has fixed thereon a guide stud 27 projecting into a cam 40 slot 28 which is formed in the plate or disk portion 7^a of the bracket 7. Said disk is fixed upon the stem 13 as by being secured to an annular flange 30 formed on said stem. It will be seen that in the rotation of the 45 bracket the member 25 of the clamping device is arranged to be operated, the cam being so shaped that in the initial movement of the bracket the jaw is moved into clamping position and held in such position 50 until lever 8 is released and the parts restored by the spring 9.

The thumb lever 8 which is operable to effect the swinging movement of the bracket 7, and hence of the tying bill 3, is rigidly 55 secured to the stem 13 by means of a screw 31. For this purpose, the end of the stem is arranged to project through the side wall of the casing section 1^a and also the portion of the hand hold 11 which is secured to said 60 wall, and is shaped to provide a non-circular end 32 (dotted lines Fig. 1) adapted to be entered into a similarly shaped opening in the lower end of the lever 8.

The spring 9, which is adapted to restore 65 the parts to normal position after an opera-

tion by the thumb lever 8, may be in the form of a torsion spring surrounding the stem 13 and having one end engaging with a stud 33 on the flange 30 and its other end rigid with the arcuate rack member 10 70 (Fig. 3).

In the use of the device, the thread ends to be united are placed in operative relation to the tying bill, being guided into this position by the rounded edge 5^a of the guide member 5 and the forward edges of the stationary members of the clamping device, which are suitably shaped for this purpose. Thereupon the operation of the thumb lever 8 swings the bracket 7 to effect, through the medium of the pinion 4 and rack 10, the rotation of the tying bill 3 and the clamping of the threads by the clamping device 6. In the initial movement of the lever the movable jaw of the clamping device is operated into clamping position while the tying bill is rotated to form the loops of the knot, in a manner well known. In the continued movement of the lever and while the threads remain clamped by the device 6, the threads are clamped by the tying bill and then severed; and in the final movement of the lever the loops are stripped from off the tying bill while the ends remain clamped thereby so as to tighten the 95 knot before the thread ends are finally withdrawn from the tying bill.

It will be seen that I have produced a knot-tying implement of a very practical character. The construction is extremely 100 simple and the actuating mechanism is advantageously arranged and wholly enclosed within a small casing from which dust and dirt are effectively excluded.

I claim as my invention:

1. A knotter comprising, in combination, a supporting structure, a stem, a bracket fixed on said stem, a spindle journaled in said bracket and extending transversely through said stem, means for rotatably securing one end of the stem to the supporting structure, a stud on the supporting structure providing a bearing for the opposite end of said stem, said spindle having within the stem an annular groove and said stud having a portion projecting into said groove whereby to prevent longitudinal movement of the spindle, a tying bill on the spindle, means for guiding and holding threads to be united in operative relation to said tying bill, means for pivotally moving said stem, and a connection between the spindle and the supporting structure for rotating the spindle in the oscillation of the stem.

2. A knotter comprising, in combination, a stationary cylindrical casing formed in two sections detachably secured together, said casing having a slot in its peripheral wall, a thread clamping device on the periphery of the casing adjacent said slot and

having a part depending into the casing, a tying bill projecting through said slot and mounted for swinging movement with reference to the casing and said clamping device, said bill having a supporting spindle projecting into the casing, and means for actuating the movable portion of the clamping device and rotating the spindle.

3. A knotter comprising, in combination, 10 a casing, a thread clamping device comprising a stationary jaw mounted on the exterior of the casing, a movable jaw adapted to co-operate with the stationary jaw and having a portion depending into the casing, 15 a tying bill swingable with reference to said clamping device, an oscillatory element mounted in the casing and arranged to rotatably support said tying bill, said element being operatively associated with the movable jaw of the clamping device to move it, means for effecting a rotation of the tying bill in the movements of said element, and means for imparting an oscillatory movement to said element.

25 4. A knotter comprising, in combination, a casing, a tying bill mounted for swinging movement relative to the casing, a thread clamping device carried by the casing and including a movable member depending into 30 the casing, an actuating element for said tying bill and thread clamping device including an oscillatory plate having an operative cam connection with said movable member of the clamping device, means for 35 rotatably supporting the tying bill, means for oscillating said element, and a gearing connection between the tying bill and the casing adapted to impart rotary movement to the tying bill in the swinging movements 40 thereof.

5. A knotter comprising, in combination, 45 a cylindrical casing, a stem mounted coaxially of the casing, a spindle extending transversely of said stem, a bracket fixed upon the stem and having portions providing bearings for the opposite ends of the 50 spindle, a pinion rigid with the spindle, an arcuate gear element rigid with the casing and intermeshing with said pinion, a tying bill carried by the spindle and projecting from the casing, thread guiding and holding means carried by the casing in operative relation to said tying bill, said holding means including a movable member projecting into the casing and into sliding engagement with said stem and also operatively associated with said bracket, and means for swinging said bracket.

6. A knotter comprising, in combination, 60 a cylindrical casing, a stem mounted coaxially of the casing, a spindle extending transversely of said stem, a bracket fixed upon the stem and having portions providing bearings for the opposite ends of the 65 spindle, a pinion rigid with the spindle, an

arcuate gear element rigid with the casing and intermeshing with said pinion, a tying bill carried by the spindle and projecting from the casing, thread guiding means carried by the casing, a thread clamping device carried by the casing, and means for swinging said bracket and hence the tying bill with reference to said thread guiding and holding means.

7. A knotter comprising, in combination, 75 a cylindrical casing, a stem rotatably mounted coaxially of the casing, a bracket fixed on said stem, a spindle rotatably mounted in said bracket, a tying bill carried by said spindle and projecting through one wall of the casing, thread guiding and holding means carried by the casing in operative relation to said tying bill, said spindle having a gearing connection with said casing whereby when the spindle is swung with the 80 bracket rotation is imparted to the spindle and the tying bill, and means for swinging the bracket and the tying bill with reference to the thread guiding and holding means.

8. A knotter comprising, in combination, 90 a sectional cylindrical casing, a stem disposed coaxially of the casing and rotatably secured to one side wall thereof, a bearing carried by the other side wall of the casing and providing a support for the opposite end of said stem, a bracket fixed upon said stem, a spindle journaled in said bracket, a tying bill carried by the spindle, a pinion rigid with the spindle, a rack fixed with reference to the casing and meshing with said pinion, thread guiding and holding means carried by the casing in operative relation to said tying bill, and means for rotating the stem to swing the bracket whereby to effect 95 rotation of the tying bill and swinging movement thereof relative to the thread guiding and holding means.

9. A knotter comprising, in combination, 100 a stationary casing formed in two sections, a tubular stem disposed on a horizontal axis in said casing, a bracket fixed on said stem, a spindle journaled in said bracket and extending transversely through said stem, means for rotatably securing one end of the stem to one wall of the casing, a stud mounted on the other wall of the casing and providing a bearing for the opposite end of said stem, said spindle having within the stem an annular groove and said stud having a portion projecting into said groove 110 whereby to prevent longitudinal movement of the spindle, a tying bill on the spindle, means for guiding and holding threads to be united in operative relation to said tying bill, and means for imparting rotary and swinging movement to the spindle and tying bill.

10. A knotter comprising, in combination, 120 a cylindrical casing, a stem rotatably mounted coaxially of the casing, a spindle jour-

naled in the stem and extending transversely thereof, thread guiding and holding means carried by the casing, a tying bill carried by the spindle, means for oscillating the stem, and means for effecting a rotation of the spindle in the swinging movements thereof.

11. The combination set forth in claim 10 wherein the means for oscillating the stem comprises a lever secured to the stem and 10 projecting beyond the peripheral wall of the casing, and a torsion spring surrounding the stem and having one end fixed thereto and its opposite end fixed with reference to the casing.

15. 12. A knotter comprising, in combination, a stationary casing, a central horizontally disposed stem rotatably mounted in the casing, a spindle, means carried by the stem within the casing providing journal bearings for the spindle, a tying bill on the spindle projecting through one wall of the casing, a thread guiding member fixed upon one side wall of the casing, a thread clamping device carried by the casing at the side 20 opposite said guide member with the tying bill between them, and mechanism operable to swing the spindle and impart rotation thereto and to actuate the clamping device.

30. 13. A knotter comprising, in combination, a stationary casing, a bracket rotatably mounted in the casing, a spindle carried by said bracket, a tying bill on said spindle projecting through one wall of the casing and movable relative thereto, thread guiding and holding means carried by the casing with reference to which means the tying bill is swingable, and means for swinging the tying bill and imparting a rotatory movement thereto.

40. 14. A knotter comprising, in combination, a stationary casing, an oscillatory element mounted in the casing, a spindle journaled in said element and having a tying bill thereon, thread guiding and holding means including a clamping device having a stationary jaw and a movable jaw, and means for oscillating said element, said tying bill and movable jaw being associated with said element whereby in the swinging movements 45 of the latter a swinging and rotatory movement is imparted to the bill and a clamping movement imparted to the movable jaw.

55. 15. A knotter comprising, in combination, a casing, an oscillatory element rotatably mounted in the casing, a spindle journaled in said element and having a gearing connection with the casing, knot-forming means carried by the spindle, thread clamping means carried by the casing and held thereby against swinging movement in the oscillation of said element, said clamping means including a movable member operatively associated with said element, and means for oscillating said element.

65. 16. A knotter comprising, in combination,

an element in the form of a casing, a second element wholly enclosed within the casing element, said elements being mounted for relative oscillatory movement, a spindle rotatably mounted within the casing but swingable relative thereto, said spindle having a gearing connection with the first mentioned element, knot-tying means including a tying bill on said spindle, and means for effecting relative movement between said elements whereby to rotate the tying bill.

17. A knotter comprising, in combination, an element in the form of a casing, a second element wholly enclosed within the casing element, said elements being mounted for relative oscillatory movement, a spindle rotatably mounted within the casing but swingable relative thereto, said spindle having a gearing connection with the first element, knot tying means including a tying bill on said spindle, a thread clamping device stationary with reference to said second element and having a movable member operatively associated with the casing element, and means for effecting relative movement between said elements whereby to rotate the tying bill and actuate the clamping device.

18. In a knotter, in combination, a supporting structure, a stem pivotally mounted therein, a spindle extending transversely through said stem, a bracket fixed upon the stem and having portions providing bearings for the opposite ends of the spindle, a pinion rigid with the spindle, a gear segment rigid with the supporting structure and intermeshing with said pinion, and a tying bill on the spindle.

19. A knotter comprising, in combination, a supporting structure, a stem pivotally mounted therein, a spindle extending transversely through said stem, a bracket fixed upon the stem and having portions providing bearings for the opposite ends of the spindle, a pinion rigid with the spindle, a gear segment rigid with the supporting structure and intermeshing with said pinion, a tying bill on the spindle, a thread guide and a thread clamp on the supporting structure and means for swinging said bracket and hence the tying bill with reference to said thread guide and said thread clamp.

20. A knotter comprising, in combination, a stationary casing, a central stem rotatably mounted in the casing, means for oscillating the stem, a spindle, means carried by the stem within the casing providing journal bearings for the spindle, a tying bill on the spindle projecting through one wall of the casing, a thread clamping device carried by the casing, and mechanism operable to rotate the spindle and actuate the clamping device in the oscillation of the stem.

21. A knotter comprising, in combination, a supporting structure, a spindle journaled

- therein, a tying bill at one end of the spindle, a clamping stripper, an operating lever, and means including a rotatable element journaled in the supporting structure and operatively associated with said lever to rotate the spindle and thereby the tying bill and effect a relative swinging movement between the clamping stripper and the tying bill.
- 10 22. A knotter comprising, in combination, a stationary casing having a tying bill projecting from one wall thereof, a clamping stripper mounted for relative swinging movement between it and the tying bill, actuating means including a rotatable element journaled in the casing, and means operatively associated with said element to rotate the tying bill and effect a relative swinging movement between it and said clamping stripper.
- 15 23. A knotter comprising, in combination, a stationary casing, a rotary tying element projecting from one wall of the casing, a thread stripping element, means for rotating the rotary element and swinging one of said elements whereby to form a knot comprising a rotatable element journaled in the casing and having an operative connection with said tying element and an operative connection between the tying element and the stripping element.
- 20 24. A knotter comprising, in combination, a stationary casing, a rotatable tying element projecting from one wall of the casing, a stripping element, means for rotating the tying element and for effecting relative swinging movement between said elements, said means including a rotatable stem journaled in the casing and an actuating member fixed with reference to said rotatable stem and having an operative connection with one of said elements to swing it.
- 25 25. A knotter comprising, in combination, a stationary casing having mounted therein a spindle, with a pinion rigid therewith, a tying bill carried by the spindle, an actuating member having gear teeth meshing with the pinion on the spindle, and means for effecting relative swinging movement between the spindle and said actuating member including an element rotatably mounted in the casing operable to swing one of said relatively movable parts.
- 30 26. A knotter comprising, in combination, a stationary casing, a rotary tying bill projecting from one wall of the casing, a member having a gearing connection with the tying bill, means for effecting relative swinging movement between the spindle and said member including a rotatable element journaled in the casing, a clamping stripper operatively associated with said member whereby a relative swinging movement
- 35 between the clamping stripper and tying bill is effected, an operating lever for rotating said element in one direction, and spring means for rotating it in the opposite direction.
- 40 27. A knotter comprising in combination, a stationary casing, a rotary tying bill projecting from one wall of the casing, a member having a gearing connection with the tying bill, means for effecting relative swinging movement between the tying bill and said member including a rotatable element journaled in the casing, a clamping stripper operatively associated with said member whereby a relative swinging movement between the clamping stripper and tying bill is effected, and cam means associated with said rotatable element for actuating the clamping stripper.
- 45 28. A knotter comprising, in combination, a supporting structure, a stem pivotally supported in said structure, a bracket fixed on said stem, a spindle journaled in said bracket, a tying bill on the spindle, guides fixed to the supporting structure at opposite sides of the tying bill for guiding and holding threads to be united in operative relation to said tying bill, means for oscillating said stem, and a connection between the spindle and the supporting structure for rotating the spindle in the oscillation of the stem.
- 50 29. A knotter comprising, in combination, a supporting structure, a stem pivotally supported in said structure, a bracket fixed on said stem, a spindle journaled in said bracket, a tying bill on the spindle, means operatively associated with the bracket for guiding and holding threads to be united in operative relation to said tying bill, means for oscillating said stem, and a connection between the spindle and the supporting structure for rotating the spindle in the oscillation of the stem, said thread-holding means being held by the supporting structure against swinging movement in the oscillation of the stem.
- 55 30. A knotter comprising, in combination, a stationary casing, a spindle having a tying bill, a thread clamp connected with the casing so as to be held thereby against swinging movement and having a movable member, and a bracket mounted for oscillatory movement in said casing, said spindle being journaled in the bracket and operatively associated with the casing and the thread clamp being operatively associated with the bracket, whereby in the oscillatory movements of the bracket the tying bill and thread clamp are actuated.
- 60 In testimony whereof, I have hereunto set my hand.

BURT A. PETERSON.
